CLAIM

The ornamental design for a sock donning aid, as shown and described.

DESCRIPTION

FIG. 1 is a top front perspective view of a sock donning aid, showing my new design;

FIG. 2 is a top rear perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The cross-hatched shading about the surface of the rectangular portion of the sock donning aid represents a textured surface.
